ADJUSTABLE SCREEN VENTILATOR FOR
WINDOWS

Gus J. Martin, New York, N. Y.

Application January 29, 1948, Serial No. 5,039

8 Claims. (Cl. 98—94)

1

This invention relates to an adjustable screen ventilator for windows.

An object of the invention is to provide a ventilator device which will tend to air condition rooms in a home, the air entering the room only through the opening in the device.

A further object is to provide a device, or ventilator, as aforesaid, which is adjustable to fit various size windows and which can be substantially sealed in the window.

Another object is to provide a ventilator as aforesaid having means for filtering the entering air.

A further object is to provide a ventilator as aforesaid having improved connections between the main part and the adjustable wings.

Still further, the present invention proposes the provision of ventilator which is entirely sealed within the window opening, and which functions to admit a controlled quantity of air through a specifically provided opening in the center of the main section.

Another object of the present invention is to construct a ventilator which may be effectively used under all types of weather conditions and which may be used to force air into the room for ventilation purposes, or which may be reversed in its action to discharge stale air from the room.

A still further object of the present invention is to provide a device having a motor operated fan for moving the air, which has all of its operating parts enclosed with a suitable housing so as to protect the same against the ruinous effects of inclement weather.

A further object of the present invention proposes an inlet opening to the motor housing provided on three sides with a suitable track system for receiving a filter designed to remove all dust particles and similar foreign matter from the air before being fed into the room.

Its further object of this invention to construct a ventilator which will effectively control drafts within the room and one which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front view of a ventilator constructed in accordance with this invention, in position in a window.

Fig. 2 is a plan of the ventilator of Fig. 1.

Fig. 3 is a plan of the main part of the ventilator of Fig. 1, the side wings being eliminated.

Fig. 4 is an enlarged vertical section taken on the line 4—4 of Fig. 1.

Fig. 5 is an enlarged section on the line 5—5 of Fig. 1.

2

Fig. 6 is an enlarged section of the line 6—6 of Fig. 1.

Fig. 7 is a perspective view of the left wing of the ventilator.

Fig. 8 is a rear view of the motor housing looking in the direction of the line 8—8 on Fig. 6.

Fig. 9 is an enlarged section on the line 9—9 of Fig. 1.

Fig. 10 is an enlarged detail of a portion of Fig. 1 through which section line 9—9 is taken.

Fig. 11 is a view, similar to Fig. 10, of that portion, with the hole therein fully exposed.

It is the purpose of the present invention to provide a ventilator which will air condition rooms in the home of a human being. The air will enter the room desired only through the opening in the ventilator, and this air is suitably filtered before it comes in contact with the fan of the ventilator so that it is in purer form than if it had been breathed directly from the atmosphere.

The ventilator is adjustable to fit in any of a series of sizes of windows and can be completely edged with foam rubber strips to assure a substantially air-tight fit in the window.

Since the ventilator is tightly held in the window opening and since it is completely edged with foam rubber striping, it will provide a closure which is air tight except for air entrance for air conditioning through the authorized port of the ventilator.

The ventilator can be used to provide ingress of cool fresh air from the outside into the room, or it can be reversed to provide egress of air from the room to the outside for clearing the room of stale air.

The ventilator includes a box-like compartment for the fan and motor, the compartment being provided with a filter so that the air entering the room can be cleansed. The filter is removable so that if the ventilator is reversed, the filter will not become contaminated by the removal of dirty air from the room.

The part of the ventilator which is normally displayed to the eye of the occupants of the room is neat and attractive in appearance. The ventilator has a main female part and lateral adjustable male wings. The top and bottom are symmetrical, the only difference being that there is an opening in the front face near the bottom for an electric cord.

The ventilator 10, constructed in accordance with the present invention, can be utilized with any one of a series of ordinary house windows 11, one such window 11 being shown in Fig. 1. The ventilator fits in the bottom and side channels 55 of the window frame 12 and the bottom sash 13 is forced down on top of the ventilator. The ventilator in any of its adjusted sizes is rectangular and when it is placed in the window, it is first stripped along its four sides with strips of foam

rubber 14, rectangular in cross section, which strips seal the window and ventilator except for the air duct of the ventilator.

The ventilator has a main female part 15. This

part is formed partly of a long rectangular piece of sheet metal provided at its center with a circular hole 16 forming part of the air duct. It is bent at its top and bottom, at right angles, to form a top wall 17 and a bottom wall 18, the remainder of the sheet forming a front wall 19, in which the hole 16 is located. A member is fastened, as by screws 20^a or the like, to each of the top and bottom walls. Each member consists of portion 20 superposed on wall 17 or 18, as the case may be, a rear flange 21, a front flange 22 and superposed on wall 19, and a channel 23 integral with front flange 22. The two channels 23 are oppositely disposed, the top one opening upwardly and the bottom one opening downwardly. At its ends, each flange 21 is cut to form tabs 21^a which are bent under and fastened to the bottom of wall 17 or 18. Each wall 20 has a slot 24 extending from each of its opposite ends toward, but not to, the middle of the ventilator, see Fig. 3.

The ventilator has two male wings 25. The wings are identical and one is shown in Fig. 7. It has a front wall 26 and top, bottom and outer end walls 27, 28 and 29 respectively. The front wall has a vertical slit 30 and is cut through its edge opposite wall 29 from slit 30 to provide top and bottom tongues 31. In its assemblage with the female portion, the walls 27 and 28 fit into the top and bottom slots 24 respectively and the tongues 31 slide in the channels 23. Thus, the overall length of the ventilator may be adjusted by sliding the male wings 25 relative to the female part 15. The male wings are designed for easy adjustment of the ventilator to different sized windows.

A box-like compartment 32 is secured to the inner face of the main female part 15 over the hole 16, this compartment being rectangular in cross section and having a flange 33 attached to the wall 19. One end of the compartment is formed on three sides with a track system 34 for receiving a filter 35. The filter 35 slides through a slot 36 formed in one of the side walls of the compartment, and the tracks extend from the compartment 32 at the top and bottom of the slot 36 to facilitate insertion and removal of the filter 35, which is provided with a knob 35^a by which it may be manually gripped. A fan 37, with an electric motor 38, is supported in the compartment, the electric cord 39 of the motor passing through a hole in the bottom of the compartment. The hole 16, in the wall 19, is covered by a wire screen 40 for safety precautions.

The fan is directed to blow cold or fresh air from the atmosphere into the room, the air passing through the filter to the fan and being forced through the screen 40 into the room. If it is desired to blow or draw the air out of the room, the entire ventilator can be reversed, placing the compartment in the room and removing the filter, or the motor can be reversed, if it is a reversible motor, the filter first being removed. The filter is made of several layers of fine wire screen.

The foam rubber substantially seals the ventilator except for the hole 16, whereby all the air entering the room must be filtered. The electric cord 39 must enter the room for connection with the usual wall socket, not shown, and a rectangular hole 41 is provided in the wall 19 for this purpose, the hole 41 being just large enough for a small male plug 42 to pass through. Since the wire 39 will occupy the hole 41 it is desired to close this hole as much as possible to maintain the air tight condition of the ventilator. To ac-

complish this, a small frame 43 is fastened to the inner face of wall 19 about the hole 41 and two small sliding doors 44 are positioned in the frame, each door 44 having a semicircular opening 45. These doors are moved apart (Fig. 11) to permit the passing of the plug 42 through the hole 41, and are moved together (Fig. 10) to leave a hole only the size of the cord 39 so that cord 39 seals the hole and no space for leakage is left. This is important for if the ventilator is reversed, the plug must be returned through the hole 41 as the compartment will then be in the room, and if the plug were not returned, it would be hanging out of the window.

It is to be understood that the openings 45 may be in the form of a deep slot and the members 44 may be of C-shape. One of these members may be left permanently in position while the other sliding door 44 may be moved to any adjusted position to accommodate the electric wire and plug.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An adjustable window screen ventilator adapted to be disposed in the side channels of a window frame and between the bottom channel thereof and the bottom sash, comprising a main female part having a front wall provided with a central air opening, top and bottom walls, a structural member secured to each of said top and bottom walls, each of said structural members having a front part superposed on said front wall, a channel at the bottom of said front part, and a rearwardly extending part at the top of said front part, said channels being oppositely disposed, the top one opening upwardly and the bottom one opening downwardly, said rearwardly extending parts being superposed over and spaced from said top and bottom walls and each having a slot extending from its outer end toward but not to the middle of said female part, and two sliding male wings for adjusting the length of said ventilator, each of said wings having a front wall disposed in front of the front wall of said female part, top, bottom and end walls, and top and bottom spaced tongues at the side of the front wall of the male wings remote from the correlated wing end wall, said top and bottom walls of the male wings sliding in said structural member slots, and said tongues sliding in said channels to restrict the male wings to lateral movement only, a box-like compartment secured to the rear face of the front wall of said female part over said air opening, and an electric motor and fan mounted in said compartment.

2. An adjustable window screen ventilator adapted to be disposed in the side channels of a window frame and between the bottom channel thereof and the bottom sash, comprising a main female part having a front wall provided with a central air opening, top and bottom walls, a structural member secured to each of said top and bottom walls, each of said structural members having a front part superposed on said front wall, a channel at the bottom of said front part, a rearwardly extending part at the top of said front part and a flange at the rear edge of said

rearwardly extending part, said channels being oppositely disposed, the top one opening upwardly and the bottom one opening downwardly, said rearwardly extending parts being superposed over and spaced from said top and bottom walls and each having a slot extending from its outer end toward but not to the middle of said female part, said flanges overlapping said top and bottom walls and being bent at their ends under their correlated top and bottom walls, and two sliding 10 male wings for adjusting the length of said ventilator, each of said wings having a front wall disposed in front of the front wall of the female part, top, bottom and end walls, and top and bottom spaced tongues at the side of the front wall of the male wings remote from the correlated wing end wall, said top and bottom walls of the male wings sliding in said structural member slots, and said tongues sliding in said channels to restrict the male wings to lateral movement only, a box-like compartment secured to the rear face of the front wall of the female part over said air opening, and an electric motor and fan mounted in said compartment.

3. A ventilator comprising a vertical main wall having an air opening, and top and bottom flanges joining the upper and lower edges of the main wall; a structural member secured to each narrow flange wall, and comprising a horizontal portion secured over and to the flange wall and a vertical flange engaged against a face of the main wall and provided with an integral edge channel, opening in a direction away from the horizontal axial part of the main wall; wing wall structures overlapping the ends of the main wall and provided with flanges engaging in said channels; a motor carrying a fan; and means for mounting the motor with the fan coaxial with said opening.

4. In an adjustable window screen ventilator, the combination of a vertical horizontally elongated front wall having a large round central air opening, and top and bottom narrow horizontal flange walls longitudinal to and joining the upper and lower edges of the main wall; a structural member secured to each narrow flange wall, and comprising a horizontal portion secured on the narrow wall and having a front flange engaged on the front face of the main wall and provided with an integral edge channel opening in a direction away from the horizontal axial part of the main wall; wing wall structures overlapping the ends of the main wall and provided with flanges engaging in said channels.

5. An adjustable window screen ventilator comprising a horizontally elongated vertical main front wall having a large round central air opening, and top and bottom horizontal flange walls longitudinal to and joining the upper and lower edges of the main wall; a structural member secured to each narrow flange wall, and comprising a horizontal portion spaced from the outer face of the narrow wall and having an intermediate slot longitudinal to the main wall, and a front flange engaged on the front face of the main wall and provided with an integral edge channel opening in a direction away from the horizontal axial part of the main wall; wing wall structures overlapping the ends of the main wall and provided with flanges engaging in said channels and with flanges extending into said slots and laterally into the spaces between said structural members and the flange wall; a motor carrying a rotary fan; and means for mounting the motor with the fan coaxial with said opening.

6. In an adjustable window screen ventilator, the combination of a vertical horizontally elongated front wall having a large round central air opening, and top and bottom narrow horizontal flange walls longitudinal to and joining the upper and lower edges of the main wall; a structural member secured to each narrow flange wall, and comprising a horizontal portion spaced from the outer face of the narrow wall and having an intermediate slot longitudinal to the main wall, and a front flange engaged on the front face of the main wall and provided with an integral edge channel opening in a direction away from the horizontal axial part of the main wall; wing wall structures overlapping the ends of the main wall and provided with flanges engaging in said channels and with flanges extending into said slots and laterally into the spaces between said structural members and the flange wall.

20 7. A ventilator comprising a horizontally elongated vertical main wall having an air opening, and top and bottom flanges joining the upper and lower edges of the main wall; a structural member secured to each narrow flange wall, and comprising a horizontal portion secured to and over the flange wall and a vertical flange engaged against a face of the main wall and provided with an integral edge channel opening in a direction away from the horizontal axial part of the main wall; wing wall structures overlapping the ends of the main wall and provided with flange parts over said flange wall and flanges engaging in said channels; said horizontal portions and said flange parts being extended in a direction longitudinal to the main wall and provided with longitudinal grooves; strips of sponge rubber in said grooves; a motor carrying a fan; and means for mounting the motor with the fan coaxial with said opening.

25 8. A ventilator comprising a vertical main wall having an air opening, and top and bottom flanges joining the upper and lower edges of the main wall; a structural member secured to each narrow flange wall, and comprising a horizontal portion secured to the flange wall and a vertical flange engaged against a face of the main wall and provided with an integral edge channel, opening in a direction away from the horizontal axial part of the main wall; wing wall structures overlapping the ends of the main wall and provided with flanges engaging in said channels; a box-like compartment secured to the main wall around said opening and having an open side opposite and remote from said air opening; a filter screen across said open side; a motor carrying a fan in said box mounted coaxial with said opening between said opening and the filter screen.
